UNITED STATES PATENT OFFICE.

ALBERT WITTNauer, OF NEW YORK, N. Y.

DESIGN FOR A BROOCH.

SPECIFICATION forming part of Design No. 34,989, dated August 27, 1901.

Application filed May 22, 1901. Serial No. 61,463. Term of patent 7 years.

To all whom it may concern:

Be it known that I, ALBERT WITTNauer, a citizen of the United States, and a resident of the city of New York, borough of Manhattan, 5 in the county and State of New York, have invented a new and original Design for a Brooch, of which the following is a full, clear, and exact description.

Reference is to be had to the accompanying 10 drawings, forming a part of this specification, in which similar characters of reference indicate corresponding parts in all the views.

Figure 1 is a front face view of a brooch, showing my design. Fig. 2 is an edge view 15 of the same; and Fig. 3 is a rear face view of a brooch, showing my design.

The design in its entirety consists of an ornamental body A, appearing at the rear with a recessed frame B and a fastening-pin C, the 20 lower ends of the body and the frame termi-

nating in spaced side arms A' B', between which appears an approximately cylindrical bearing D, having an opening D' standing at an angle to the pin C.

The main feature of the design consists of 25 the ornamental body A, the depending spaced side arms, and the apertured bearing D between the side arms.

Having thus fully described my invention, I claim as new and desire to secure by Letters 30 Patent—

The design for the brooch herein shown and described.

In testimony whereof I have signed my name to this specification in the presence of 35 two subscribing witnesses.

ALBERT WITTNauer.
